UNITED STATES PATENT OFFICE

ARTHUR F. O'CONNOR, OF CHICAGO, ILLINOIS, ASSIGNOR TO EQUIPMENT SPECIALTIES COMPANY, OF CHICAGO, ILLINOIS, A CORPORATION OF ILLINOIS

SUPPORT CONSTRUCTION

Application filed July 25, 1931. Serial No. 553,234.

My invention relates in general to refrigerator apparatus and has more particular reference to railroad refrigerator cars, relating especially to a novel means for and 5 method of supporting the brine tanks therein.

In structures of this general class heretofore provided, it has been the custom to support the brine tanks on a steel structure resting in turn on metal pedestals, usually castings, supported upon the bottom of the drip pans, which are usually of galvanized iron and which are ordinarily placed beneath the brine tanks to collect condensed moisture or 10 other drippage from the tanks. Due to the weight of the loaded brine tanks and vibration of the refrigerator car in transit, the pedestals or support castings quickly wear holes through the bottom of the drip pans 15 with the result that water leaks out of the pans and rots the wooden frame of the car and the expensive insulation below the drip pan. The drip pans, being also of galvanized iron, are susceptible to rusting at the 20 points where the cast iron pedestals rest thereon so that deterioration of the parts in structures heretofore provided is relatively 25 rapid.

An important object of my invention 30 therefore is to provide means for supporting the brine tanks in such a way as to relieve the bottom of the drip pan from the contributing causes of deterioration.

Another important object of the invention 35 is to eliminate all metal brine tank supports in the drip pan.

A further object of the invention is to provide an improved support structure for brine tanks in which an adjustment is provided to 40 accommodate for the sagging of the support frame, which comprises a relatively long span across the width of the refrigerator car.

Another object of the invention is to provide truss rods for strengthening the frame 45 and to render these rods adjustable to increase the trussing effect in order to offset sagging of the structure.

Another feature of my invention resides 50 in the method of securing the ends of the truss rods on the frame.

Numerous other objects and advantages will be understood from the following description, which taken in connection with the accompanying drawing, discloses a preferred embodiment of the invention. 55

Referring to the drawing:

Figure 1 is a longitudinal section taken through the end of a refrigerator car having a brine tank support construction embodying my present invention; 60

Figure 2 is a vertical section taken substantially along the line 2—2 in Figure 1;

Figure 3 is a top plan view of a portion of the brine tank support embodying my present invention; 65

Figures 4 and 5 are vertical sections taken substantially along the lines 4—4 and 5—5 respectively in Figure 3; and

Figure 6 is a perspective view of the brine tank support structure. 70

To illustrate my invention, I have shown on the drawing, the end of a refrigerator car 11 having a floor 12, side and end walls 13, and a roof structure 14 of any suitable or desired construction, the whole being mounted 75 on bogies 15 in the usual manner employed in the construction of railroad rolling stock. The walls, floor and roof of the car 11 are provided with insulation 16 in a manner well known in the art, which insulation may be 80 of any suitable or desired form and construction.

The end of the car is preferably provided with a lateral partition 17 dividing the car 85 into a goods compartment 18 and a compartment 19 at the end of the car for housing the brine tanks 20. A drip pan 21, preferably formed as a shallow galvanized iron pan, extending lengthwise preferably completely throughout the width of the compartment 19 90 and having its end edges engaging the inner faces of the opposite side walls 13, and arranged on the floor of the compartment 19 with an edge preferably engaging the inner surface of the end wall 13'. The drip pan 95 21 may, of course, be of any usual or preferred construction and the brine tanks are carried on a support structure 22 illustrated in entirety in Figure 6 of the drawing and which comprises preferably a frame of angle 100

irons, which rests at its opposite ends on preferably wooden blocks 23, which are or may be positioned in the opposite ends of the drip pan.

5 The support member 22 comprises a pair of spaced apart longitudinal frame members 24, the ends of which are fastened and connected in spaced relationship by angle irons 25 at opposed ends of the frame. The members 24 10 preferably comprise angle irons 26 and truss members 27 comprising a strap fastened at their opposed ends to the ends of the horizontal flanges 28 of the angle irons 26, the ends of the strips 27 being provided with bent 15 lips 29 extending around and into engagement with the end edges of the horizontal flanges 28 and the strap 27 being riveted or otherwise secured as by the fasteners 30 near the ends of the horizontal flanges 28 as 20 shown in Figure 5 of the drawing. The center portions of the members 24 also are connected together by a connecting and spacing member 31, the opposite ends of which are bolted or otherwise secured preferably to 25 the horizontal flanges 28 of the members.

I prefer, however, to provide each member with a plate 32, which is riveted or otherwise secured as by the fastening members 33 to the underside of the horizontal flange 28.

30 The plates extend inwardly and provide means to which the opposite ends of the spacing bar 31 may be secured as by means of the bolts 34. The members 26 also are provided with a perforation 35 preferably

35 at the middle of the horizontal flange 28 and the plate 32, being applied to the flange at this point, is also provided with a perforation 36 in alignment with the perforation 35. The strap 27 also is provided, immediately beneath the aligned perforations 35 and 36,

40 with a fitting 37 bolted or otherwise secured thereto, which fitting preferably carries an upstanding threaded shank 38, the upper end of which is adapted to extend into and through the channel provided by the perforations 35 and 36. The threaded shank 38

45 is or may be provided with an adjusting nut 39 and a lock nut 41, the former being adapted to engage the under surface of the plate 32 so that by adjusting the nut 39 on the threaded shank 38, the mid-portions of the truss strap 27 may be forced away from the angle iron 26 and since the strap 27 is fastened to the ends of the member 26, an ad-

50 justable trussing action is thus provided. The lock nut 41 is, of course, to secure the adjusting nut 39 in adjusted position on the shank 38 as is well known in the art.

55 The longitudinal truss members 24 rest upon and are secured on the horizontal flange 42 of the end members 25, which are preferably relieved as at 43 to receive the projecting ends of the fastening members 30, which extend downwardly of the strap 27; and one 60 of the truss members 24, that one which ex-

tends adjacent the end wall 13 of the refrigerator car when the support is assembled in operative position, is preferably positively fastened to the end members as by the nutted bolt 44. The other truss member, however, is preferably formed to simply rest upon the flanges 42 of the end members and is held in place by means of angle brackets 45, one arm 46 of which extends upwardly and engages the vertical flange of the angle 75 arm 26 and the other arm 47 of which is secured to the flange 42 as by means of the bolts 48 or any other suitable fastener. By means of this construction, the front truss member 24 may be readily removed in order to facilitate the demounting of the brine tanks 20, it being merely necessary to remove the bolt 34 by which said front member is fastened to the spacing member 31 to permit the front member 24 to be raised in the frame, the brine 85 tanks being slightly tipped back on their rearmost edges to permit the front truss member 24 to be removed after which the brine tanks may be readily moved forwardly 90 out of the compartment 19, it being understood that the partition 17 is removable for this purpose.

The horizontal flanges 28 also are provided with preferably wooden slats 49, which are secured to the upper surface of the flanges 95 28, as by means of the fastening members 50, which are preferably countersunk beneath the upper surface of the slats. The brine tanks 20 rest at their front and rear edges on the wooden slats 49.

100 As a result of this construction, the relatively inexpensive, readily replaceable slats will wear out rather than the more expensive, difficultly replaceable brine tanks with resulting operating economy.

105 It will be noted also that the support frame is mounted in the drip pan on wooden blocks 23, which are preferably bolted to the horizontal flanges of the end members, said flanges being provided with perforations 51 by which such bolting may be accomplished so that here again the wear on the drip pan is considerably reduced since the weight of the support frame is carried to the drip pan through the relatively large 110 wooden blocks 23. These blocks obviously are relatively inexpensive and may be easily replaced when worn, or otherwise damaged in service.

115 The unusual strength and rigidity provided in the frame by the truss strap 27 and the adjustment accomplished by means of the threaded shank 38 and nut 39 is extremely valuable in that it prevents the longitudinal frame members from sagging and also provides means for straightening the member in order to offset any sagging which may be imparted in the frame because of the relatively heavy loaded brine tanks. By adjusting the nut 39 from time to time, the frame may 120

be maintained in properly braced condition in order to prevent same from setting in sagged position.

- Another feature of advantage resides in 5 the method of securing the ends of the truss rods to the frame members. In order to take the strain off the fastening members, the end of the truss rod or strap is bent around the end of the support member.
- 10 It is thought that the invention and numerous of its attendant advantages will be understood from the foregoing description and it is obvious that numerous changes may be made in the form, construction, and arrangement of the several parts without departing from the spirit or scope of my invention or sacrificing any of its attendant advantages; the form herein described being a preferred embodiment for the purpose of illustrating 15 my invention.

Having thus described my invention, what I claim as new and desire to secure by Letters Patent is as follows:

1. The combination, with a refrigerator 25 compartment having brine tanks and a drip pan, of a support structure for said brine tanks in said drip pan, and blocks of relatively soft, easy-wearing material disposed in the drip pan under the opposite ends of 30 the support.
2. The combination, with a refrigerator compartment having brine tanks and a drip pan, of a support structure for said brine tanks comprising a longitudinal truss member, 35 and blocks of relatively easy-wearing material detachably mounted on opposite ends of the frame in position to support said frame in said drip pan.
3. The combination, with a refrigerator 40 compartment having brine tanks and a drip pan, of a support structure for said brine tanks comprising a frame having longitudinal truss members and end pieces to which the ends of the support members are connect- 45 ed in spaced relationship and means in said drip pan for supporting the end pieces.

4. The combination, with a refrigerator 50 compartment having brine tanks and a drip pan, of a support structure for said brine tank comprising a substantially rectangular frame having a longitudinal member, a truss member for the longitudinal member and means to adjust the truss member, end pieces 55 engaging and supporting the longitudinal member in position to support the brine tanks and means in the drip pan to carry said end members.

5. The combination, with a refrigerator 60 compartment having brine tanks and a drip pan, of means to support the brine tanks comprising a substantially rectangular frame providing spaced-apart, longitudinal support members on which the brine tanks are mounted, means to maintain the support 65 members in spaced tank-supporting position

and means to support the rectangular frame above the drip pan, a said longitudinal support member comprising a beam and a truss associated with said beam to maintain it in substantial non-sagging condition.

6. The combination, with a refrigerator compartment having brine tanks and a drip pan, of means to support the brine tanks comprising a substantially rectangular frame providing spaced-apart, longitudinal support members on which the brine tanks are mounted, means to maintain the support members in spaced tank-supporting position and means to support the rectangular frame above the drip pan, a said longitudinal support member comprising a beam, a truss associated with said beam to maintain it in substantial non-sagging condition and means to adjust the truss.

7. A support structure comprising a frame 85 having a longitudinal truss member on which to support brine tanks and the like, said support member comprising a beam, a truss connected at its opposite ends to the opposite ends of the beam, threaded means co-operat- 90 ing between the beam and the truss strap intermediate the ends thereof for adjusting the trussing action and supporting means at the ends of the beam.

8. A support structure comprising a frame 95 having a pair of spaced apart support members on which to carry brine tanks and the like, end members engaging and supporting the support members in position to receive and support the brine tanks, one of said support members being securely fastened at its opposite ends to the end members and another of the support members having its ends unfastened so that it can be readily removed from the structure to permit dismantling of 100 the brine tanks therefrom.

9. A support structure comprising a frame having a longitudinal truss member on which to carry brine tanks and the like, said support member comprising a beam, a truss member connected at its opposite ends to the opposed ends of the beam, said truss member being fastened to a side of the beam near the end thereof and having a portion extending to and around the end of the beam whereby 110 the engagement of said truss member with the end of the beam may reduce the shear at the point of attachment thereof on the side of the beam.

10. A support structure comprising a sub- 120 stantially rectangular frame providing spaced apart longitudinal support members on which to carry brine tanks and the like, said longitudinal support members comprising angle irons arranged in the frame with their vertical flanges facing outwardly and their horizontal flanges extending inwardly, slats of relatively resilient, long-wearing material on the upper surfaces of the horizontal flanges, truss means comprising a strap 125 130

fastened at its opposite ends to the opposed ends of the support members and an adjustable spacing member extending between the medial portions of the support member and the strap, end members engaging the opposite ends of the support members to carry the same in spaced-apart, tank-supporting position and blocks of relatively resilient, easy-wearing material detachably mounted to the end members and extending downwardly thereof to furnish support for said frame.

In witness whereof, I have hereunto subscribed my name.

ARTHUR F. O'CONNOR.
